Robert Murray MacRobbie, Brooklyn, N.Y., assignor to
Richmond Screw Anchor Co., Inc., Brooklyn, N.Y.
Filed Apr. 17, 1964, Ser. No. 360,587
8 Claims. (Cl. 248—354)

This invention relates to devices for adjusting and maintaining the position of one construction element relative to another and more particularly to that category of devices generally known as tilt-up wall braces.

It is a general object of the invention to provide an improved tilt-up wall brace which is easily manufactured at low cost.

Another object of the invention is to provide an improved tilt-up wall brace, wherein provision is made for coarse and fine length adjustments.

Still another object of the invention is to provide an improved wall brace having a double-acting or amplified fine length adjustment.

Yet another object of the invention is to realize improved compression characteristics at a minimum expenditure of material and labor.

In accordance with one aspect of the invention there is provided a base comprising first and second brackets with first and second elements pivotally coupled thereto and adapted for being supported in coaxial alignment, there being further provided rotatable means extending between and connecting these elements and threadably engaging the latter with oppositely directed threads whereby to adjust the distance between the above-noted brackets.

According to a further aspect of the invention there is provided a brace comprising first and second brackets and a series of adjustably connected elements extending between and connecting these brackets, at least one of these elements including a conical portion of work-hardened steel whereby an improved compression characteristic is realized without any significant expenditure of material and/or labor.

According to still another aspect of the invention, there is contemplated a brace comprising first and second brackets with first and second elements pivoted thereto and coarse and fine length adjusting means serially connected between these elements, the fine length adjusting means having oppositely direct threaded connections with one of the above-noted elements and said coarse adjusting means for effecting adjustment therebetween.

In accordance with one embodiment of the invention there is contemplated the provision of coarse adjustment means which includes at least one wooden beam adapted to be cut to length at the site of construction.

According to a second embodiment of the invention there is contemplated the provision of a coarse adjustment means comprising a rigid tube having axially spaced holes therein with means selectively positionable in these holes to effect a connection between the rigid tube and one of the above-noted pivotable elements.

The above objects and features of the invention, as well as advantages thereof, will become apparent from the following detailed description of some preferred embodiments of the invention as illustrated in the accompanying drawing in which:

FIGURE 1 is a side view of a tilt-up wall brace provided in accordance with one embodiment of the invention and shown in relation to two constructional elements, the relative positions of which are to be adjusted;

FIGURE 2 is a top plan view of a bracket employed in the arrangement of FIG. 1;

FIGURE 3 is a side view of the bracket of FIG. 2;

FIGURE 4 is a side view of a component employed in the wall brace of FIG. 1;

2

FIGURE 5 is an end view of the component of FIG. 4;
FIGURE 6 is a side view of a further component employed in the wall brace of FIG. 1;

FIGURE 7 is an end view of the component of FIG. 6;
FIGURE 8 is a side view of still another component employed in the wall brace of FIG. 1;

FIGURE 9 is an end view of the component shown in FIG. 8;

FIGURE 10 is a side view of a support employed in the wall brace of FIG. 1;

FIGURE 11 is a top plan view of the support of FIG. 10; and

FIGURE 12 is a side view of a tilt-up wall brace provided in accordance with another embodiment of the invention.

In FIG. 1 is generally indicated a tilt-up wall brace 10 employed in accordance with the invention to adjust the relative position of a vertical construction element 12 with respect to a horizontal construction element 14.

The wall brace 10 comprises generally a bracket 16 connected, as will be shown, to the construction element 12 and a bracket 18 connected, as will be shown, to the construction element 14.

Pivots connected to the brackets 16 and 18 are pipe elements 20 and 22.

To the pipe element 22 is connected an adjusting means or stud 24 to the free end of which is connected a third pipe element 26.

Respectively connected to pipe elements 20 and 26 are supports 28 and 30, between which extend wooden beams 32 and 34, which will be discussed in greater detail hereinafter.

As will be shown, the adjustment stud 24 has operatively associated therewith a rod 36, by means of which a threadable adjustment is made between pipe elements 22 and 26, constituting a fine adjustment, the wooden beams 32 and 34 being adapted for being cut to length at the site of the construction and constituting a coarse adjustment for the wall brace, as will become evident hereinafter.

Brackets 16 and 18 are shown in greater detail in FIGS. 2 and 3 wherein it is seen that each bracket comprises a base 38 and two upstanding flanges 40 and 42, which are parallel to each other and spaced at a distance adapted to accommodate the extremity of pipe element 22, as will be shown hereinafter.

The base 38 of each bracket is provided with an elongated slot 44, which is disposed generally perpendicularly relative to the flanges 40 and 42 and which opens laterally in the said base. The slot 44 is moreover provided with a rounded terminal portion 46, to accommodate the shank of a bolt or the like.

Flanges 40 and 42 are respectively provided with openings or holes 48 and 50, which are coaxially aligned for a purpose which will become apparent hereinafter.

The brackets described above may be fabricated from a material having suitable constructional strength, such as malleable iron.

The first and second pipe elements 20 and 22 of FIG. 1 are shown in greater detail in FIGS. 4 and 5, wherein it is seen that each of said pipe elements comprises a flatted end portion 52, a generally cylindrical or second end portion 54 and an intermediate or connecting portion 56 of generally truncated conical shape.

The intermediate portion 56 includes a narrow extremity 58 which is connected with and merges with the end portion 54 and further includes a broad extremity 60 which merges with and is connected to the flattered end portion 52.

The flatted end portion 52 comprises diametrically opposed holes or openings 62 and 64 which are adapted for

being aligned with the holes 48 and 50 of the flanges 40 and 42 of FIGS. 2 and 3, so as to be able to accommodate the passage therethrough of a bolt 66 (FIG. 1) which receives thereon a nut 68 which cooperatively lock the pipe element 22, for example, to the bracket 18, an equivalent pivotal connection being provided between the pipe element 20 and the bracket 16.

Each pipe element (FIGS. 4 and 5) is generally circular in cross-section with the exception of the flattened end portion and is moreover hollow and is further provided with an internal thread 70 in the second end portion 52, the purpose of said thread made hereinafter apparent.

FIGS. 6 and 7 illustrate the details of the adjustment stud 24 of FIG. 1.

In FIGS. 6 and 7 it is seen that the adjustment stud generally comprises first and second end portions 72 and 74 of generally hollow cylindrical form, there being provided an intermediate portion 76 provided with a diametral passage 78 extending therethrough.

The intermediate portion 76 connects end portions 72 and 74 to each other in coaxially aligned relationship.

Intermediate portion 78 may be of hollow form or alternatively may be of solid form, in which event the diametral passage 78 extends completely therethrough.

End portions 72 and 74 are respectively provided with exterior threads 80 and 82, the exterior thread 80 being engaged with the interior thread 70 of the pipe element 22 (see FIG. 1).

The adjustment stud 24 may be made of any material having suitable constructional strength, such as steel or iron.

As has been heretofore noted, the adjustment stud 24 constitutes a fine length adjustment for the tilt-up wall brace of the invention and to this end the threads 80 and 82 are oppositely directed although being in coaxial relationship, this provision being discussed in greater detail hereinafter. The fine adjustment is, however, effected through the intermediary of the rod 36 (FIG. 1) which is accommodated in the diametral passage 78, either with a fixed friction fit or by being welded to the adjustment 40 stud 24, as desired.

The details of the third pipe element 26 are illustrated in FIGS. 8 and 9 wherein it is seen that this element comprises a first end portion 84 and a second end portion 86, the latter end portion having a smaller diameter than the end portion 84.

Pipe element 26 moreover comprises an intermediate conical portion 88 which connects the end portions 84 and 86 in coaxial relationship.

Each of the end portions is provided with an internal or interior thread, there being provided an internal thread 90 for end portion 84 and an internal thread 92 for end portion 86.

Pipe element 26 is made of a suitably strong material such as steel or iron or the like and the internal thread 92 of end portion 86 is engaged with the external thread 82 on end portion 74 of the adjustment stud 24.

The details of supports 28 and 30 are shown in FIGS. 10 and 11 wherein it is seen that each support comprises a base 94 with a center flange 96 extending upwardly 60 therefrom so as to form therewith an inverted T-beam.

Depending from the base 94 are a plurality of arcuate segments 98, 100, 102 and 104 concentrically arranged to constitute a cylindrical component which in turn constitutes a connecting element by virtue of the provision of exterior thread 106 which is provided on said arcuate segments.

The thread 106 of the support 28 is engaged with the corresponding internal thread of the pipe element 20 and the thread 106 of the support 30 is engaged with the interior thread of the end portion 84 of the pipe element 26.

Wooden beams 32 and 34 are spaced parallel wooden beams fabricated of any wood having suitable strength and readily available at a construction site of usual type.

These beams straddle the center flanges 96 of the supports 28 and 30 respectively.

To provide for the connection of the wooden beams 32 and 34, the center flanges 96 are respectively provided with holes or openings 108 and 110.

The beams 32 and 34 abut against the bases 94 of supports 28 and 30 and are squared thereagainst. Bolts 112 and 114, as well as bolts 116 and 118 are employed to fixedly secure the beams 32 and 34 to the supports 28 and 30.

The provision of the adjustment stud 24 with the oppositely directed threads provides a fine adjustment technique for use in association with the tilt-up wall brace of the invention. The use of the two oppositely directed threads permits an amplified or double-acting adjustment.

At the same time the provision of wooden beams 32 and 34 permits of a coarse adjustment, inasmuch as these beams can be cut to length at the site of the construction.

Elements 22 and 26 are pipe elements having large diameters which enhance the compression strength of the overall wall brace construction, it being noted that these elements along with adjustment stud 24 and beams 32 and 34 cooperatively constitute a rectilinear structure adapted for having compressive stresses applied thereto when the element 12 tends to pivot or fall down against the construction element 14.

In accordance with the invention, the elements 20, 22 and 26 are cold worked or swaged in order to work harden these elements so as to provide a maximum strength at a minimum cost.

These principles are carried over to the embodiment of the invention illustrated in FIG. 12, wherein like elements are assigned like reference characters.

The embodiment of FIG. 12 similarly comprises brackets 12 and 14, pipe elements 20' and 22, and adjustment stud 24.

Pipe element 20' is provided with an extension in the form of a further pipe element 120, which is an elongated hollow cylindrical tube having a series of axially spaced holes 122 positioned therein.

In this embodiment of the invention there is provided a pipe element 124 which is an elongated version of the pipe element 26 of FIG. 1, said pipe element 124 having an internal thread 126 adapted to engage the exterior thread of adjustment stud 24 for purposes of the double acting or amplified fine length adjustment which has been noted above.

Pipe element 124 comprises a cylindrical end portion 128 and a cylindrical end portion 134 of elongated construction, these end portions being connected by a conical intermediate portion 132 formed in the cold working manner which has been noted above.

Pipe section 124 is provided with a series of axially spaced holes 134, these holes being alignable with the holes 122 in pipe section or extension 120.

The pipe section 120 and the pipe section 124 are in telescopic relationship such that the passage of a bolt 136 through aligned holes in these elements provides for a coarse adjustment of length of the overall wall brace.

From what has been described above, it will now be apparent that the invention provides an improved tilt-up wall brace which is easily manufactured at low cost.

It will be further apparent that the invention provides an improved tilt-up brace wherein provision is made for coarse and fine length adjustments.

It is still further apparent, in view of the above explanation, that the invention provides an improved wall brace having a double acting or amplified fine length adjustment and further than the invention provides for improved compression characteristics in the use of cold work connecting pipe elements.

There will now be obvious to those skilled in the art many modifications and variations of the structure set forth above. These modifications and variations will not

depart from the scope of the invention if defined by the following claims.

What is claimed is:

1. A wall brace for bracing one element relative to another, said wall brace comprising first and second brackets adapted for connection to respective of said elements, each bracket including a base provided with an elongated slot opening laterally of the base and having a rounded terminal portion, each bracket further including spaced parallel flanges perpendicularly connected to the associated base and provided with coaxially aligned holes, said flanges being perpendicular to said slots, first and second generally circular pipe elements of hollow construction including flattened end portions extending between the flanges of a respective one of said brackets and provided with holes aligned with the holes in the associated brackets, bolts extending through the holes in the flanges and flattened end portions for pivotally connecting the latter to said flanges, said pipe elements each further including a second end portion of hollow cylindrical form including an internal thread and a hollow intermediate portion of generally truncated conical form having a narrow extremity merging with and connected to the associated second end portion and a broad extremity merging with and connected to the associated flattened end portion, adjustment means including coaxial directed threads, one of which is engaged with the internal thread of the second end portion of one of the pipe elements, a third pipe element including first and second cylindrical end portions of different diameter and a conical portion connecting the latter said end portions in coaxial relation, the latter said end portions including internal threads, the other thread of the adjustment means being engaged with the internal thread of the smaller of the end portions of the third pipe element, first and second supports each comprising a T-beam including a base and a center flange, each support further comprising a connecting element depending from the associated base and including a plurality of arcuate segments cooperatively constituting a cylindrical component having an external thread, the thread of the respective cylindrical components respectively engaging the internal thread of the larger end portion of the third pipe element and the internal thread of the second end portion of the other of the first two said pipe elements, each center flange being provided with at least one opening therein, a pair of parallel spaced wooden beams extending between said supports, straddling said center flanges and squaring against the bases of the supports, and bolts passing through and connecting the beams and center flanges such that the beams, pipe elements, supports and stud constitute a rectilinear structure of adjustable length.

2. A wall brace for bracing one construction element relative to another, said wall brace comprising first and second generally circular pipe elements of hollow construction including flattened end portions, means for pivotally connecting the flattened end portions to said construction elements, said pipe elements each further including a second end portion of hollow cylindrical form including an internal thread and a hollow intermediate portion of generally truncated conical form having a narrow extremity merging with and connected to the associated second end portion and a broad extremity merging with and connected to the associated flattened end portion, an adjustment stud including two end portions of generally hollow cylindrical form including exterior threads which are oppositely directed and an intermediate portion connecting the latter said portions in coaxial relation and provided with a diametral passage, the exterior thread of one of the end portions of said stud being engaged with the internal thread of the second end portion of one of the pipe elements, a rod extending through said diametral passage, a third pipe element including first and second cylindrical end portions of different diameter and a conical portion connecting the latter end portions in

coaxial relation, the latter said end portions including internal threads, the exterior thread of the other of the end portions of said stud being engaged with the internal thread of the smaller of the end portions of the third pipe element, first and second supports each comprising a T-beam including a base and a center flange, each support further comprising a connecting element depending from the associated base and including a plurality of arcuate segments cooperatively constituting a cylindrical component having an external thread, the thread of the respective cylindrical components respectively engaging the internal thread of the larger end portion of the third pipe element and the internal thread of the second end portion of the other of the first two said pipe elements, each center flange being provided with at least one opening therein, a pair of parallel spaced wooden beams extending between said supports, straddling said center flanges and squaring against the bases of the supports, and bolts passing through and connecting the beams and center flanges such that the beams, pipe elements, supports and stud constitute a rectilinear structure of adjustable length.

3. A wall brace for bracing one element relative to another, said wall brace comprising first and second brackets adapted for connection to respective of said elements, each bracket including a base provided with an elongated slot opening laterally of the base and having a rounded terminal portion, each bracket further including spaced parallel flanges perpendicularly connected to the associated base and provided with coaxially aligned holes, said flanges being perpendicular to said slots, first and second generally circular pipe elements of hollow construction including flattened end portions extending between the flanges of a respective one of said brackets and provided with holes aligned with the holes in the associated brackets, bolts extending through the holes in the flanges and flattened end portions for pivotally connecting the latter to said flanges, said pipe elements each further including a second end portion of hollow cylindrical form including an internal thread and a hollow intermediate portion of generally truncated conical form having a narrow extremity merging with and connected to the associated second end portion and a broad extremity merging with and connected to the associated flattened end portion, an adjustment stud including two end portions of generally hollow cylindrical form including exterior threads which are oppositely directed and an intermediate portion connecting the latter said portions in coaxial relation and provided with a diametral passage, the exterior thread of one of the end portions of said stud being engaged with the internal thread of the second end portion of one of the pipe elements, a rod extending through said diametral passage, a third pipe element including first and second cylindrical end portions of different diameter and a conical portion connecting the latter said portions in coaxial relation, the latter said end portions including internal threads, the exterior thread of the other of the end portions of said stud being engaged with the internal thread of the smaller of the end portions of the third pipe element, first and second supports each comprising a T-beam including a base and a center flange, each support further comprising a connecting element depending from the associated base and including a plurality of arcuate segments cooperatively constituting a cylindrical component having an external thread, the thread of the respective cylindrical components respectively engaging the internal thread of the larger end portion of the third pipe element and the internal thread of the second end portion of the other of the first two said pipe elements, each center flange being provided with at least one opening therein, at least one wooden beam extending between said supports, and means for connecting the beam and center flanges such that the beam, pipe elements, supports and stud constitute a rectilinear structure of adjustable length.

4. A wall brace for bracing one element relative to another, said wall brace comprising first and second brackets adapted for connection to respective of said elements, each bracket including a base provided with an elongated slot opening laterally of the base and having a rounded terminal portion, each bracket further including spaced parallel flanges perpendicularly connected to the associated base and provided with coaxially aligned holes, said flanges being perpendicular to said slots, first and second generally circular pipe elements of hollow construction including flattened end portions extending between the flanges of a respective one of said brackets and provided with holes aligned with the holes in the associated brackets, bolts extending through the holes in the flanges and flattened end portions for pivotally connecting the latter to said flanges, said pipe elements each further including a second end portion of hollow cylindrical form including an internal thread and a hollow intermediate portion of generally truncated conical form having a narrow extremity merging with and connected to the associated second end portion and a broad extremity merging with and connected to the associated flattened end portion, an adjustment stud including two end portions of generally hollow cylindrical form including exterior threads which are oppositely directed and an intermediate portion connecting the latter said portions in coaxial relation and provided with a diametral passage, the exterior thread of one of the end portions of said stud being engaged with the internal thread of the second end portion of one of the pipe elements, a rod extending through said diametral passage, a third pipe element including first and second cylindrical end portions of different diameter and a conical portion connecting the latter said end portions in coaxial relation, the latter said end portions including internal threads, the exterior thread of the other of the end portions of said stud being engaged with the internal thread of the smaller of the end portions of the third pipe element, first and second supports each comprising a T-beam including a base and a center flange, each support further comprising a connecting element depending from the associated base and including a plurality of arcuate segments cooperatively constituting a cylindrical component having an external thread, the thread of the respective cylindrical components respectively engaging the internal thread of the larger end portion of the third pipe element and the internal thread of the second end portion of the other of the first two said pipe elements, each center flange being provided with at least one opening therein, a pair of parallel spaced wooden beams extending between said supports, straddling said center flanges and squaring against the bases of the supports, and bolts passing through and connecting the beams and center flanges such that the beams, pipe elements, supports and stud constitute a rectilinear structure of adjustable length.

5. A brace comprising first and second brackets, first and second means respectively pivotally coupled to said brackets and adapted for being supported in coaxial alignment, said first and second means including respective sleeve elements which are axially spaced from one another in axially aligned relation, rotatable means extending between and connecting said sleeve elements and threadably engaging the latter with oppositely directed threads whereby to adjust the distance between the sleeve elements and therefore between the brackets, said sleeve elements including conical end portions which threadably engage the rotatable means, said conical end portions being work hardened metal, said rotatable means and sleeve elements constituting fine length adjusting means, one of said first and second means including coarse length adjusting means in axial relation with the fine length adjusting means, said coarse length adjusting means comprising at least one beam having opposite end portions with approximately perpendicular surfaces, first and second support means secured to a respective end portion of

the beam and engaging the same along the perpendicular surfaces thereof to seat said surfaces, said support means each including threaded portions projecting in an axial direction away from the beam, the threaded portion of one of said support means being in threaded engagement with the sleeve element of said one of the first and second means, the latter said one means including a further sleeve element pivotally coupled to its associated bracket, the threaded portion of the other of the support means being in threaded engagement with said further sleeve element.

6. A wall brace for bracing one construction element relative to another, said wall brace comprising first and second generally circular pipe elements of hollow construction including end portions, means for pivotally connecting the end portions to a construction element, said pipe elements each including a threaded portion, adjustment means including oppositely directed threads in coaxial relation, one of the threads of the adjustment means being engaged with the thread of one of the pipe elements, a third pipe element including a threaded portion, the other thread of the adjustment means being engaged with the thread of the third pipe element, first and second supports each comprising a T-beam including a base and a center flange, each support further comprising a connecting element depending from the associated base and including a plurality of arcuate segments cooperatively constituting a cylindrical component having an external thread, the thread of the respective cylindrical components respectively engaging the thread of the third pipe element and the thread of the other of the first two said pipe elements, each center flange being provided with at least one opening therein, a pair of parallel spaced wooden beams extending between said supports, straddling said center flanges and squaring against the bases of the supports, and bolts passing through and connecting the beams and center flanges such that the beams, pipe elements, supports and adjustment means constitute a rectilinear structure of adjustable length.

7. A wall brace for bracing one construction element relative to another, said wall brace comprising first and second generally circular pipe elements of hollow construction including flattened end portions, means for pivotally connecting the flattened end portions to a construction element, said pipe elements each further including a second end portion of hollow cylindrical form including an internal thread and a hollow intermediate portion of generally truncated conical form having a narrow extremity merging with and connected to the associated second end portion and a broad extremity merging with and connected to the associated flattened end portion, adjustment means including coaxial directed threads, one of which is engaged with the internal thread of the second end portion of one of the pipe elements, a third pipe element including first and second cylindrical end portions of different diameter and a conical portion connecting the latter said end portions in coaxial relation, the latter said end portions including internal threads, the other thread of the adjustment means being engaged with the internal thread of the smaller of the end portions of the third pipe element, first and second supports each comprising a T-beam including a base and a center flange, each support further comprising a connecting element depending from the associated base and including means constituting a cylindrical component having an external thread, the thread of the respective cylindrical components respectively engaging the internal thread of the larger end portion of the third pipe element and the internal thread of the second end portion of the other of the first two said pipe elements, at least one beam extending between said supports adjacent said center flanges and squaring against the bases of the supports, and means connecting the beam and center flanges such that the beam,

pipe elements, supports and adjustment means constitute a rectilinear structure of adjustable length.

8. A wall brace for bracing one construction element relative to another, said wall brace comprising first and second pipe elements of hollow construction, means for pivotally connecting the pipe elements to a construction element, said pipe elements each further including an end portion remote from the associated construction element of hollow cylindrical form including an internal thread, adjustment means including exterior threads which are oppositely directed and one of which is engaged with the internal thread of the end portion of one of the pipe elements, a third pipe element including end portions with internal threads, the other of the exterior threads of the adjustment means being engaged with the internal thread of the third pipe element, first and second supports each comprising a T-beam including a base and a center flange, each support further comprising means depending from the associated base and constituting a cylindrical component having an external thread, the thread of the cylindrical component respectively engaged the internal thread of the third pipe element and the internal thread of the other of the first two said pipe elements, a beam extending between said supports adjacent said center flanges and squaring against the bases of the supports,

5

and means connecting the beam and center flanges such that the beam, pipe elements, supports and adjustment means constitute a rectilinear structure of adjustable length.
